PIPE PILE POINT

John J. Dougherty, 262 Rutherford Blvd.,
Cedar Grove, N.J.

Filed Oct. 2, 1963, Ser. No. 76,833

Term of patent 14 years

(Cl. D54—9)

FIG. 1

FIG. 2

FIG. 3

FIG. 1 is a bottom plan view of a pipe pile point, showing my new design.

FIG. 2 is a side elevational view thereof.

FIG. 3 is a cross-sectional view taken on the line 3—3 of FIG. 1.

I claim:

The ornamental design for a pipe pile point, as shown.
